(57) **CLAIM**

I claim the ornamental design for a table lamp, as shown and described.

DESCRIPTION

FIG. I is a front perspective view of a table lamp showing my new design;

FIG. 2 is a rear perspective view of FIG. 1;

FIG. 3 is a front elevational view of FIG. 1;

FIG. 4 is a rear elevational view of FIG. 1;

FIG. 5 is a left side elevational view of FIG. 1;

FIG. 6 is a right side elevational view of FIG. 1;

FIG. 7 is a top plan view of FIG. 1; and,

FIG. 8 is a bottom plan view of FIG. 1.

The broken lines shown in the drawings are included for the purpose of illustrating elements of the table lamp that form no part of the claimed design.

The table lamp is shown with a symbolic break in its length. The appearance of any portion of the article between the break lines forms no part of the claimed design.
